UNITED STATES PATENT OFFICE.

JOSEPH SACHS, OF HARTFORD, CONNECTICUT, ASSIGNOR TO THE SACHS COMPANY, OF HARTFORD, CONNECTICUT, A CORPORATION OF CONNECTICUT.

SAFETY-FUSE.

No. 874,798.

Specification of Letters Patent.

Patented Dec. 24, 1907.

Application filed April 18, 1906, Serial No. 312,302. Renewed September 11, 1907. Serial No. 392,369.

To all whom it may concern:

Be it known that I, JOSEPH SACHS, a citizen of the United States, residing at Hartford, in the county of Hartford and State of Connecticut, have invented an Improvement in Safety-Fuses, of which the following is a specification.

My invention relates to safety fuses of the type used with telegraph and telephone systems and adapted for very small current service. In the past such fuses have been constructed of heating coils or springs consisting of resistance wires; one end of each of the springs or coils being joined together by fusible solder so that when the current is passed through the convolutions of the coiled springs which were kept under tension, the heat produced would cause the melting of the fusible joint and hence a rupture or opening at this point. The objection to this construction in the past has been due to the fineness of the wires necessary in the construction of the coiled springs and the difficulty of assembling and maintaining them in a rigid position, and hence, as heretofore constructed, such fuses have been readily injured by handling both in construction and service, causing the joint to be ruptured mechanically.

The object of my present invention is to provide a construction for this type of fuse which will insure rigidity and permanency in the heat coil structure and I accomplish this result by providing the heating coils and the wires extending from their ends to the circuit terminals with a suitable holder having located therein a pocket in which the coiled portion and joint are protected.

In carrying out my present invention, I preferably employ a casing, terminals thereon, a holder of insulating material fitting within said casing, and provided centrally with a pocket, resistance wires, each connected at one end with one of said terminals, extending into the said holder and having a coiled portion within the said pocket, and a fusible connection between the coiled ends of said wires within the said pocket.

In the drawing, Figure 1 is a central longitudinal section illustrating my improved safety fuse. Fig. 2 is a similar section taken at right angles to that shown in Fig. 1. Fig. 3 is a section on line *x*, *x*, Fig. 2. Fig. 4 is a section on line *y*, *y*, Fig. 2. Fig. 5 is a plan,

Fig. 6 an edge view of a modification of my present invention, and Fig. 7 is a section illustrating a modification of the form of invention shown in Figs. 1 to 4 inclusive.

a designates a tube or cylinder preferably made of a good insulating material and *b*, *b*, 60 represent end caps or ferrules, or as I prefer to call them in this case,—terminals.

c is a holder of insulating material preferably made in one piece and folded over to fit diametrically within the tube *a* with the adjacent faces glued or otherwise secured together, or made in two or more pieces suitably fastened together, or otherwise as may be desired, but in any instance the holder *c* is provided with a pocket 2, formed preferably 65 centrally by depressions in the respective members thereof and the pocket 2 may be entirely inclosed or open at one side and along one edge of the strip *c* as shown in Fig. 7. 75

d, *e*, designates wires preferably of German silver or other high resistance material, each electrically connected at one end to a terminal *b* passing between the parts of the strip *c* and into the pocket 2 therein, where 80 these wires are coiled as shown at 3, 4, respectively, and their inner ends are electrically connected by a drop of solder 5 or other fusible material, and if desired, the ends of the tube *a* between the terminals and the ends of the strip *c* may be filled with an asbestos fiber or other insulating material as indicated at 6. 85

It will be apparent that the coiled ends of the wires within the pocket of the said holder not only concentrate the heat produced in the wire but also being under tension, effect a separation of the extremities thereof when the joint is ruptured, and that the delicate fuse structure is protected by being supported 90 rigidly within the holder. 95

While I prefer to employ a tubular casing provided with suitable terminals it will be understood that I may dispense with the tube without departing from the nature and spirit of my invention, and as shown in Figs. 5 and 6, I may employ terminals *b'* *b'*, between which are clamped the respective ends of the holder *c'* of insulating material in which the pocket 2 is formed. Resistance wires *d'* *e'* are each connected at one end to a terminal *b'* and extend through the strip *c'* into the pocket 2 where the other ends of the wires 100 105

are coiled as at 3, 4, respectively and the extremities are electrically connected by the fusible joint 5.

I claim as my invention:

5 1. A safety fuse comprising terminals, a holder of insulating material, a pocket integral with said holder and wires connected at one end with the respective terminals, and at the other electrically connected with each 10 other by a fusible joint within the said pocket.

15 2. A safety fuse comprising terminals, a two-part holder of insulating material, a pocket in said holder, and high resistance wires electrically connected at one end to the respective terminals and coiled within said pocket at their other ends with the extremities of the coils electrically connected by a fusible joint.

20 3. A safety fuse comprising terminals, a two-part holder of insulating material with the parts thereof secured together, a pocket formed by the parts of said holder, and high resistance wires electrically connected at one 25 end with the respective terminals and passing between the parts of said holder and at the other ends coiled and electrically connected by a fusible joint within said pocket.

4. A safety fuse comprising a tube, terminals therefor, a holder of insulating material, a pocket in said holder and wires connected at one end with the respective terminals and passed into said holder and at the other electrically connected with each other 35 by a fusible joint within the said pocket.

5. A safety fuse comprising a tube, terminals therefor, a holder of insulating material, a pocket in said holder, and high resistance wires electrically connected at one end 40 to the respective terminals and passed into said holder and at the other coiled with their extremities electrically connected by a fusible joint within said pocket.

45 6. A safety fuse comprising a tube, terminals thereon, a two-part holder of insulating material with the parts thereof secured together, a pocket formed by the parts of said holder, and high resistance wires electrically connected at one end with the respective terminals and passing between the parts of said holder and at the other ends coiled and electrically connected by a fusible joint within said pocket.

7. A safety fuse comprising a holder of 55 insulating material, a pocket therein, heating

coils under tension in said pocket, and a fusible joint connecting one end of each coil within the pocket, the other ends extending through the holder.

8. A safety fuse comprising a tube, terminals thereon, a holder of insulating material within said tube, a pocket in said holder, heating coils within said pocket, and a fusible joint connecting one end of each coil within the pocket, the other ends extending 65 through the said holder and being electrically connected to the said terminals.

9. A safety fuse comprising a tube, end caps thereon, a holder of insulating material within said tube, a pocket in said holder, heating coils within said pocket, and a fusible joint connecting one end of each coil within the pocket, the other ends extending through the said holder and being electrically connected to the said end caps.

75 10. A safety fuse comprising a flat strip of insulating material with its parts so folded and connected together as to provide a pocket therein centrally of its length, heating coils in said pocket, and a fusible connection between the ends of the coils in the pocket, the other ends of the coils extending to the opposite extremities of said strip.

11. A safety fuse comprising a tube, terminals therefor, a flat strip of insulating material within said tube and having its parts so folded and held together as to provide a pocket therein, centrally of its length, heating coils in said pocket, and a fusible connection between the ends of the coils in the 90 pocket, the other ends of the coils extending to the opposite extremities of the said strip and being electrically connected to said terminals.

12. A safety fuse comprising a tube, end caps therefor, a flat strip of insulating material within said tube and having its parts so folded and held together as to provide a pocket therein centrally of its length, heating coils in said pocket, and a fusible connection 100 between the ends of the coils in the pocket, the other ends of the coils extending to the opposite extremities of the said strip and being electrically connected to said end caps.

105 Signed by me this 9th day of April, 1906.
JOSEPH SACHS.
